Attorney, Agent, or Firm—Plevy & Associates

[57] CLAIM

The ornamental design for a surgical headlight, as shown and described.

DESCRIPTION

FIG. 1 is a perspective view of a surgical headlight of my new and original design, with the broken line showing for illustrative purposes only and forming no part of the claimed design;

FIG. 2 is a front plan view thereof;

FIG. 3 is a rear view thereof;

FIG. 4 is a side view thereof;

FIG. 5 is a top view thereof;

FIG. 6 is a bottom view thereof; and,

FIG. 7 is another perspective view showing the focusing rod removed from the headlight collar.
